PACKAGING CONTAINER FOR NEEDLES OR THE LIKE

Jean Jacques Lechat, Eupen, Belgium, assignor to Manufacture Belge d'Aiguilles, Eupen, Belgium, a corporation of Belgium

Filed June 12, 1961, Ser. No. 65,547

Term of patent 14 years

(Cl. D58—12.6)

FIG. 1

FIG. 2

FIG. 3

FIG. 4

FIG. 5

FIG. 6

FIG. 1 is a top plan view of a packaging container for needles or the like showing my new design, the needles shown therein in broken lines are for illustrative purposes only;

FIG. 2 is a side elevational view thereof;

FIG. 3 is a top plan view of the transparent sliding cover;

FIG. 4 is a cross section of the cover taken across the lines 4-4 of FIG. 3;

FIG. 5 is a top view of the body of the container; and FIG. 6 is a cross section of the body taken along the lines 6-6 of FIG. 5.

I claim:

The ornamental design for a packaging container for needles or the like, as shown and described.
